UNITED STATES PATENT OFFICE.

ANTHONY HESSELS, OF NEW YORK, N. Y.

COLLAR-BUTTON.

SPECIFICATION forming part of Letters Patent No. 339,775, dated April 13, 1886.

Application filed February 17, 1886. Serial No. 192,207. (No model.)

To all whom it may concern:

Be it known that I, ANTHONY HESSELS, a resident of the city of New York, in the county of New York and State of New York, have invented certain new and useful Improvements in Collar-Buttons, of which the following is a specification.

The main defect of collar-buttons made and used heretofore has been that the bottom disk usually had its outer surface made convex, so that only the central portion of said disk rested against the skin and chafed the same, thus making the button inconvenient, and causing a greater or less abrasion of the skin.

15 The object of my invention is to provide a new and improved collar-button which has its bottom disk so constructed that it fits snugly against the front or back of the neck, and is thus very convenient for the wearer.

20 The invention consists in a collar-button having its bottom disk made oval and curved in the direction of its length on a slightly convex line, so as to conform to the curvature of the neck, said button being provided with 25 a flat shank, post, or stem, all as will be fully described hereinafter, and then pointed out in the claims.

In the accompanying drawings, Figure 1 is a side view of my improved collar-button. 30 Fig. 2 is an end view of the same. Fig. 3 is a view of the under side of the bottom disk.

Similar letters of reference indicate corresponding parts.

The button is composed of the head A, the shank, post, or stem B, and the bottom disk, C. The head A is of the usual construction, and may be ornamented in any suitable manner, or constructed to hold a gem. The bottom disk, C, is made oval or elliptical, and has its under side curved in the direction of the major axis of the ellipse or oval on a convex line, so as to adapt the under side of said plate or disk to fit snugly against the front or back of the neck. The post B is made flat, 45 and is fixed to the upper side of the bottom

disk, C, parallel with the major axis of said disk.

The button-holes in the neckbands of shirts are usually cut transversely to the length of the shirt, and if the flat stem B is passed through the button-holes it will be held with its flat sides transversely to the length of the shirt, and thus the major axis of the disk C will be held transversely to the length of the shirt, whereby the disk C will be held in position so that its convex under side can fit against the neck. The entire under surface of the bottom disk rests against the neck, and thus the pressure of the button is not concentrated in one point, but distributed over the entire under surface of said bottom disk. As the flattened shank or post is in the button-hole, the button is prevented from turning. The button is thus very convenient and cannot chafe the skin or produce eruptions. 65

A further advantage of my improved button is that the shank or stem can be made shorter than in collar-buttons of the ordinary construction, and thus material is saved.

Having thus described my invention, I claim 70 as new and desire to secure by Letters Patent—

1. A collar-button having its bottom disk made elliptical or oval and having its under surface convexly curved on a line of the major axis of said bottom disk, substantially as shown 75 and described.

2. A collar-button having its bottom disk made oval or elliptical and having its under surface convexly curved on a line of the major axis of the disk, the button being also constructed with a flat stem, shank, or post, which is parallel with the major axis of the bottom disk, substantially as shown and described. 80

In testimony that I claim the foregoing as my invention I have signed my name in presence of two subscribing witnesses. 85

ANTHONY HESSELS.
